UNITED STATES PATENT OFFICE.

HENRY A. DE KAY, OF POCOMOKE CITY, MARYLAND.

PACKAGE.

SPECIFICATION forming part of Letters Patent No. 597,395, dated January 18, 1898.

Application filed December 17, 1896. Serial No. 616,062. (No model.)

To all whom it may concern:

Be it known that I, HENRY A. DE KAY, a citizen of the United States, residing at Pocomoke City, in the county of Worcester and 5 State of Maryland, have invented a new and useful Package, of which the following is a specification.

This invention relates to an envelop, case, or package for receiving articles—such as 10 bonnets, hats, &c., for ladies, gentlemen, and children—and aims to provide a collapsible case which can be stored in a small space when not required for service and which will prevent the flexible sides from crowding against 15 the trimmings of ladies' and misses' hats and injuring them.

The package consists, essentially, of a paper sack and a pasteboard bottom, the latter having the lower edge portion of the sack 20 pasted thereto and holding the sides of the sack distended when the article is placed therein.

The package or paper sack is reinforced at 25 its open end by a textile strip cemented thereto and having a series of openings for a string or lace to be rove through, by means of which the open end of the sack is held shut when closed. The open end of the sack is stiffened at opposite sides by strips which have open- 30 ings for the string or lace to pass through, and the portions extending between the adjacent ends of the strips form bellows flaps, which fold inward and are clamped between the stiffening-strips, and thereby completely 35 close the mouth of the package when the hat or article is placed therein.

For a full understanding of the merits and advantages of the invention reference is to be had to the accompanying drawings and the 40 following description.

The improvement is susceptible of various changes in the form, proportion, and the minor details of construction without departing from the principle or sacrificing any of 45 the advantages thereof, and to a full disclosure of the invention an adaptation thereof is shown in the accompanying drawings, in which—

Figure 1 is a perspective view of a package 50 constructed in accordance with this invention. Fig. 2 is a plan view showing the parts as they will appear when the package is closed.

Fig. 3 is a perspective view of a modification. Fig. 4 is a detail section of the stiffened edge portion of the package.

55

Corresponding and like parts are referred to in the following description and indicated in the several views of the drawings by the same reference-characters.

The principal object of the invention is to 60 provide a wrapper or envelop for milliners' use which can be constructed cheaply, so as to provide a commercial article of this character which will cost but a trifle more than the ordinary paper sacks generally employed 65 as wrappers for receiving hats and bonnets and which will prevent injury to the trimmings of the hat or bonnet and be capable of subsequent use as a box or package for receiving the hat when not required for immediate 70 service.

The wrapper, envelop, or package comprises a paper sack 1, having a bottom 2, of pasteboard or similar cheap material, which will provide a stiff bottom, so as to hold the 75 sides of the sack expanded and prevent them crowding against the hat or article placed within the package. This constitutes the invention in its simplest form, as shown in Fig. 3, and after the article is placed within the 80 sack the open end of the latter is gathered and secured by wrapping a string or applying a suitable binder thereto.

In the preferable form, as shown in Figs. 1 and 2, the open end of the sack is reinforced 85 by a textile strip 3, which is secured in place by being gummed or cemented to the sack. Stiffening-strips 4 are applied to the open end 90 of the sack at opposite points and are secured between the body of the sack and the textile strip. A series of openings 5 are formed at intervals in the length of the textile strip and receive the string or lace 6, by means of which the open end of the package is made fast and held closed when shut. The portions of the 95 sack comprised between the contiguous ends of the stiffening-strips 4 fold in the manner of bellows flaps and come between the stiffening-strips 4 and are held by drawing the stiffening-strips together by means of the 100 string 6, a loose end portion of the latter being passed through the middle opening of each strip, thence returned through the said openings after being passed around the portion of

the string extending across the middle opening of one of the stiffening-strips, the ends of the string being tied any way found most advantageous.

5 The package herein described can be quickly constructed, and its use is not limited merely to serving as a wrapper, as the package is designed for service as a hat box or receptacle to be used frequently as boxes specially designed for this purpose, and the package being flexible can be reduced to a compact form, so as to occupy a minimum amount of space when not in use.

Having thus described the invention, what

15 is claimed as new is—

A milliner's wrapper or package consisting of a paper sack, a pasteboard bottom pasted to the lower edge of the sack to hold the latter distended when in use and prevent the crowding of its sides against the hat or bon-

net, stiffening-strips cemented or gummed to the outer side of opposite edge portions of the sack at its mouth, a reinforcing textile strip cemented to the outer upper edge portion of the sack and extending over the stiffening- 25 strips, and a string rove through middle and end openings in the stiffening-strips and through corresponding openings in the reinforcing-strip and the bellows flaps formed at the sides of the sack between the stiffening- 30 strips to draw said bellows flaps between the stiffening-strips when closing the sack, substantially as set forth.

In testimony that I claim the foregoing as my own I have hereto affixed my signature in 35 the presence of two witnesses.

HENRY A. DE KAY.
